UNITED STATES PATENT OFFICE

2,499,670

BOILER DEVICE

George S. Neeley, Pacific, Mo.

Application May 17, 1944, Serial No. 535,922

3 Claims. (Cl. 122—4)

1

This invention relates to a boiler device, and more particularly it relates to an apparatus and method for eliminating the pitting, corrosion and foaming that frequently characterize boiler operations, or, to a lesser degree, metallic liquid containers.

It is an object of the invention to provide a method of and a means for accomplishing the foregoing objectives, including the resultant increase in efficiency of the boilers.

More particularly, it is an object of the invention to provide a method and means that are inexpensive and that have no parts to be moved or adjusted.

More particularly, it is an object of the invention to provide a means to control electric potentials that are present in a metallic liquid container, such especially as a boiler, and to do so without introducing additional undesirable electric potentials.

It is a further object to provide a means of this kind designed to cooperate with a foam trough installation on a boiler.

In the drawings:

Fig. 1 is a vertical sectional view, partly broken away, of a conventional locomotive boiler with the installation therein,

Fig. 2 is a partial section on the line 2—2 of Fig. 1; and

Fig. 3 is a partial section on the line 3—3 of Fig. 1.

This application is a continuation in part of application Serial No. 413,712, filed October 6, 1941 (now abandoned).

The boiler shown includes an outer sheet 10, a fire box casing 12 having an end sheet 13, a flue sheet 14 and a crown sheet 15. There is a mud ring 17 to which the crown sheet 15 and the outer sheet 10 are secured. The usual tubes 18 are secured to the flue sheet 14. A steam dome 16 is attached at the top of the outer sheet 10 in conventional fashion.

The water in the boiler is indicated at W, above which is a steam space S.

Many locomotives are equipped with foaming troughs 20 secured as by straps 21 to the outer sheet above the water line and beneath the steam dome 16. These parts are conventionally made of sheet material of the same composition as that of the outer sheet, the parts usually being sheet steel.

The present invention comprises an electrode unit 25 comprising two tubes 26 and 27 formed of the same material as the tubes 18 of the boiler, and, in deed, which may be made of sections of discarded tubes. The two tubes 26 and 27 are permanently and electrically united to a U-shaped supporting strap 28, the legs of which are turned over the upper part of the trough 20 and tightly and electrically secured thereto. The parts should be welded. The strap 28 is similarly

2

made of sheet material of the same chemical composition as that of the tubes 26 and 27.

It will be seen that the tubes 26 and 27 are disposed below the water line and in close proximity to the boiler tubes 18, but are spaced therefrom. The spacing is desirably about 2½ inches from the tubes. The only direct connection between the electrode 25 and the tubes 18 is through the water itself. Tests have shown that the most desirable location for the electrode 25 in an installation such as that illustrated is immediately below the steam dome 16.

In setting up the apparatus, observation is made of the location of scale. This is expected to be at the heat-receiving areas, and principally around the tubes in boilers. At this area an electrode is inserted into the water, then cold, in close proximity to the said area, and held away from the metal parts. It may be supported by insulated legs or straps. An electric lead, duly separated from the metal parts of the boiler, is brought outside the shell. Then with a millivoltmeter, with one terminal connected to the lead, spot readings are taken to various metallic parts of the boiler. At the point of maximum potential thus discovered, the lead from the electrode is fastened electrically. The installation is then complete, and thereafter no changes need be made. Or, if desired and convenient, supporting means, such as those here illustrated, may be employed for the joint functions of support and conduction. Thus, for the illustrated installation, the foregoing test showed maximum scaling at the tubes and the points of highest potential to be around the steam dome 16. In conformity with the teachings of the invention, therefore, the electrode 25 is located with respect to the tubes 18, as shown and described, and the straps 28, the trough 20, and the straps 21 form, in addition to supporting structures, an electrical conductor connecting the electrode 25 to the outer sheet 10. The points at which the straps 21 are connected to the outer sheet 10 are approximately those observed to exhibit the highest potential under the above-described tests.

It is, of course, not absolutely essential that the connection be made at the point of maximum reading, although such is desirable. Also, when the optimum point is known, a rigid supporting connection may be made, whereby the supporting means for the electrode and the electrical connection are both embodied in the same structural elements, without repetition of the voltage testing.

In most boilers, the point of maximum potential is found to be between the electrode and the shell above the water line and adjacent the steam outlet.

It has also been determined that the electrode must be of substantial coverage by way of area.

In large equipment, two or more electrodes or collectors may be used. In the boiler illustrated, two tubes are used to extend the coverage. Obvious alternatives are the use of cross members on the rods, or the use of mesh electrodes. A convenient rule of thumb is to embrace within the limits of the electrode an area equal to about one-third of the area of the metal parts that scale. Also it is desirable to extend the electrode to within a few inches of the ends of the tubes.

It has been observed that the potential difference between the electrode and the shell will diminish after connection to the shell of the terminal from the electrode until it becomes zero. Thereafter it will remain zero as long as the equipment is in place. An illustrative time period for this elimination of potential is thirty minutes to one hour.

In a typical water storage tank illustration, a pipe, connected electrically to the top of the tank (by integrally attaching it directly into the top of the tank with an integral connection of the type described above) and depending centrally to adjacent the bottom, has proved satisfactory. The electrode should be of substantially the same metal as the tank, to avoid introducing additional electrolytic conditions into the tank.

Tests made on a number of different boilers have shown that upon installing this equipment a marked reduction in pitting, foaming and scaling has resulted, along with a substantial increase in boiler efficiency.

To illustrate, a certain boiler had continually suffered from corrosion despite the use of chemicals and various other devices on the market for correcting the same. City authorities finally offered the operators only one more limited period to correct this condition before insisting upon reducing the capacity of the boiler greatly. Without guarantee, this device was installed in the boiler. The installation was the same as shown herein, except that the strap 28 was secured directly and electrically to the outer sheet 18 above the water line, an obvious alternative used when the boiler does not already have the foam trough. Thereafter, the foaming in this particular installation was reduced substantially to zero, and the boiler was permitted by the city officials to continue operation at its high rating.

In another boiler, scaling, corrosion, and foaming were giving serious trouble. After this device had been in use for several months, these problems were all eliminated, and a fuel saving of 33 1/3 % was found.

The apparatus has been installed on many other boilers during the course of the preceding months with uniform good results and with a complete lack of necessity for any adjustments or attention whatever. This is in contradistinction to the use of external electrical power devices, and to the use of devices inserted into the boiler, of metals substantially different from the metal of the boiler. In the latter, according to one authority, an electrical action is produced, but with the trouble that the different metal itself introduces additional reactions that are too frequently deleterious. In the present case, the evidence indicates that there is an electrical action involving ionization of the impure water, but that this electrical action is reduced to zero by the presence of the apparatus, this latter being in contradistinction to the introduction of other and different electrical action, as by external cells or an internal cell formed by the presence of dissimilar metal.

The tests further show a substantial saving in fuel consumption and the elimination of the need for boiler compounds, which, without the apparatus, constitute an item of substantial expense in boiler operation.

What is claimed is:

1. A protector device for metallic containers for holding liquid to a predetermined liquid level with a space within the container above the liquid, comprising a metal collector, means supporting the collector within the container below the liquid level, and with the metal of the collector separated from the metal of the container below the liquid level, electrical conducting means connecting the collector to the interior of the container above the water line, and integral joints between the conducting means, the container and the collector forming them into an integral group, the metal portions of the device below the liquid level having substantially the same electrolytic properties as the metal of the container to which the device is connected.
2. A protector apparatus for boilers having a metallic shell adapted to contain water to a level, and having a space above the water, including a metal collector, means supporting the collector below the water line of the shell, and with the metal of the collector and the metal of the shell below the water level, separated from each other, means electrically connecting the collector and the interior of the shell above the water line, said means including at least one electrical conductor integrally joined to the collector and integrally joined to the interior of the shell above the water line, the metal portions of the device below the water level, including that of the collector and that of the connecting means, having substantially the same electrolytic properties as those of the shell.
3. A protector device for metallic containers for holding liquid to a predetermined level with a space within the container above the liquid, the protector device comprising a collector formed of metal of substantially the same electrolytic properties as those of the container, the collector having a portion disposed below the liquid level of the container, but with the metal of the portion out of electrical contact with metal of the container below the liquid level, the collector having a portion integral with the first-named portion, extending above the liquid level, and means integrally connecting the last-named portion to the metal of the container above the liquid level, whereby that portion of the collector below the liquid level and the container above the liquid level are integrally connected for transmission of electric energy of minute character, between them.
